VACUUM PICKUP

Edgar R. Miller, Chicago, Ill., assignor to F. J. Littell Machine Company, Chicago, Ill., a corporation of Illinois

Application June 15, 1940, Serial No. 340,765

5 Claims. (Cl. 294—64)

The invention relates to improvements in an implement or tool for feeding punch presses and the like and has reference particularly to a vacuum pick-up which will have a secure grip upon relatively small metal sheets, plates and other work-pieces so that they can be fed without endangering the workmen.

The present device is in the nature of a safety tool since the vacuum created will cause plates, sheets or other metal articles to adhere to the flexible suction cup and accordingly the operator of the tool can insert the same into or withdraw the work-piece from the press without subjecting his hands or fingers to danger. The suction created is produced by a venturi orifice as the result of the flow through said orifice of a fluid medium such as compressed air under relatively low pressure.

Another object of the invention is to improve the plate lifter shown in my Patent No. 2,200,800 by rearranging the parts thereof for the greatest efficiency in operation, for accessibility of the parts in case of repair or replacement, and for reasons of economy in case of damage to the suction gripping cups which are constantly exposed to the moving dies of punch presses and like machines.

A more specific object is to provide a tool or implement of the vacuum pick-up type with improved pistol grip and which will embody as a substantially integral part thereof a venturi member and associated elements for creating a vacuum by the flow of air under pressure.

A further object is to provide a pistol grip for a tool as described having a substantially horizontal passage in the head portion for receiving the venturi elements and also having other passages for the flow of the fluid under pressure and a suction passage, all of said passages being so related as to simplify manufacture and produce the most efficient type of device.

With these and various other objects in view, the invention may consist of certain novel features of construction and operation as will be more fully described and particularly pointed out in the specification, drawings and claims appended hereto.

In the drawings which illustrate an embodiment of the invention, and wherein like reference characters are used to designate like parts—

Figure 1 is a top plan view of the improved vacuum pick-up tool of the invention;

Figure 2 is a vertical sectional view showing the interior construction of the pistol grip and suc-

tion gripping cup of the tool illustrated in Figure 1;

Figure 3 is an enlarged fragmentary sectional view taken on line 3—3 of Figure 2;

5 Figure 4 is an enlarged fragmentary sectional view taken on line 4—4 of Figure 2;

Figure 5 is a side elevational view showing a modified form of the invention including an adjustable handle member secured to the pistol

10 grip;

Figure 6 is a side elevational view showing in detail the handle adapter; and

Figure 7 is an end view of the adapter.

Referring to the drawings, the device of the 15 invention essentially consists of a pistol grip indicated by numeral 10, a tubular supporting arm 12 projecting forwardly from the pistol grip and a flexible gripping cup 14 suitably supported in depending relation from the supporting arm 12.

20 Upon actuation of the trigger 11 air under pressure from the hose 13 will flow through the Venturi passage to be presently described, producing a suction which is communicated by the tubular arm 12 to the gripping cup 14. If the cup 25 is placed upon a metal article such as a plate or sheet, or any material substantially impervious to the air, sufficient suction will be created to cause the article to adhere to the gripping cup whereby the same may be bodily lifted by the operator and deposited any place desired merely by 30 termination of the suction.

The pistol grip is provided with a cored opening 15 in the handle portion 16 thereof for purposes of lightness, whereas, the bore 17, parallel

35 thereto, connects at one end with the supply hose 13 for air under pressure and at its upper end with a valve chamber 18 having threads 19 for a part of its length threadedly receiving the

40 valve body 20. The valve plunger 21 having the valve head 22 is adapted to have axial movement within the valve body so as to move toward or away from the valve seat 23. The valve plunger 45 is backed by a spring 24 and normally the passage 17 is closed off at the valve chamber since the spring maintains the head 22 firmly in contact with the seat 23. Actuation of the trigger 11, however, will cause the valve to move axially inward, allowing air to flow past the valve seat

50 into the radial passage 25, Figure 4, to the circular connecting chamber 26, and from said chamber it will be observed that the air under pressure may readily flow into the vertical bored opening 27 which in effect provides a continuation of the bore 17, the same being intercepted

by the trigger actuated valve located in the valve chamber as described.

The bored opening 27 extends vertically downward from the top surface of the head portion 28 of the pistol grip, having communication at its lower end with the valve chamber. Said opening is normally closed at the upper surface of the head portion 28 by the threaded screw 29. A second bored opening 30 is formed in the head portion 28, the same being disposed substantially parallel with opening 27, and which is also closed at its upper end by the threaded screw 31. The lower end of opening 30 connects with a horizontal passage 32 into which is threaded the coupling member 33. By means of the clamping sleeve 34 the tubular supporting arm 12 is releasably secured to the coupling member and thus to the pistol grip in communicating relation with the horizontal passage 32 comprising the suction passage of the device.

The suction cup block 35 is suitably fastened to the terminal end of the tubular supporting arm 12. By means of the tubular screw 36 and washer 37 the suction cup is releasably held to the block 35, it being observed that the screw is threaded into said block and that a passage 38 extends axially the length of said screw. As a result of this passage the interior of the flexible suction cup 14 is connected with the bore extending through the arm 12 and thus the suction from the suction passages 30 and 32 is communicated to the interior of the tube.

In this improved form the venturi member and associated elements are located within a substantially horizontal passage 40 in the head portion 28 of the pistol grip. Said passage is internally threaded and the rear end of said passage, which is somewhat larger in diameter than the forward portion thereof, receives the jet holder 41 which is suitably locked in proper oriented position by the set screw 42. The venturi member 43 is threaded into the discharge end of passage 40 and is retained in adjusted position by the lock nut 44. The bore through the venturi member is provided with an intermediate reduced section 45 which connects with the terminal end portions of the bore by means of gradually tapering sections 46. The jet holder 41 has a central opening 47 extending rearwardly from its nose end for substantially the full length of the holder. This central opening at its closed end has communication by means of the radial passages 48 and the circular connecting chamber 49 with the vertical bored opening 27 described as forming a continuation of the opening 17 connecting with the supply of air under pressure. The jet 50 extends forwardly from the central opening 47 of the jet holder and is thereby positioned within the bore of the venturi member 43. This association of the jet within the venturi member takes place in advance of the intersection of the vertical opening 30 with the transverse passage 40. As a result the suction produced by the discharge of air from the jet into the bore of the venturi member is accordingly communicated to the suction passages 30 and 32, to the tubular supporting arm 12 and thus to the flexible suction gripping cup 14.

In operation of the device air under pressure from the hose 13 will be admitted to the vertical opening 27 only when the trigger 11 is actuated to displace the valve stem 21 with respect to its seat 23 against the tension of spring 24. From the vertical opening 27 the air will flow through radial passages 48 into the central opening 47 75

of the jet holder and through jet 50 which has an exact adjustment with the member 43 so as to discharge the air into the venturi throat 45. The actual amount of suction will depend upon the pressure of the discharge through jet 50 and of course the same may be varied by adjusting the relationship of the venturi member with respect to said jet. During the time air under pressure is being discharged through the venturi member the suction gripping cup 14 may be placed upon a metal article such as a sheet or plate and the suction created will be sufficient to cause them to adhere to the cup so that they will be moved bodily for placement within a punch press or the like.

The suction cup and supporting parts are sometimes damaged since this end of the device is moved into and out of the danger zone of the punch press many times in the course of a working day. However, in the present construction any damage to this end of the device is limited to the suction cup only, all the more expensive parts of the venturi being located within the head portion of the pistol grip. This constructional feature is important in reducing the maintenance cost in connection with the present safety tool. Also by locating the venturi member and associated parts within the head portion of the pistol grip it is possible to service the same as access thereto is relatively easy and manufacturing operations are also simplified.

It is possible to bore all the passages in the pistol grip and only two, namely, 18, providing the valve chamber, and 40, which receives the venturi member and jet holder, are required to be threaded. The longitudinal bore including the openings 17 and 27 extends from end to end of the pistol grip and has intersecting relation in the head portion of the pistol grip with passage 40 which extends transversely from one side to the other of the handle. The opening 30 leading to passage 32 and comprising the suction passage also has intersecting relation with the transverse passage and the vacuum producing means located within the transverse passage is positioned relatively close to this intersection, more particularly to one side of the same, and which is on the side opposite the longitudinal bore. Whatever may be the location of the vacuum producing means within the transverse passage it is necessary that communication be established between the same and the suction passages.

In the modification of the invention the pistol grip 10 is provided with an adapter 51 for securing to the pistol grip an auxiliary handle member 52, as shown in Figures 5, 6 and 7. The head portion 28 of the pistol grip has a rounded top surface for the greater portion of its length, interrupted at spaced points by upstanding bosses 53 having a flat top surface, Figure 3. Since the handle adapter is applied to the top surface of the head portion of the pistol grip the undersurface of the adapter, Figure 7, is formed with a radius 54 which is provided with depressions 55 intermediate its length for receiving the flat topped boss 53. In other words, the undersurface of the handle adapter 51 has a shape which is complementary to the upper surface of the handle portion of the pistol grip. It will be understood that the screws 29 and 31 are removed before the adapter is positioned on the top surface of the handle portion and in order to hold the same in place on the pistol grip threaded screws 56 and 57 are employed which are some-

what longer than screws 29 and 31 and which extend not only through the handle adapter but also into the threaded openings in the head portion from which the screws 29 and 31 were removed. Accordingly, 56 and 57 may be considered as substitutes for the screws otherwise employed in the pistol grip and which function in a manner similar thereto to hermetically seal the transverse passage 40 in the pistol grip.

The upstanding flange member 58 is an integral part of the handle adapter which, however, has a thickness substantially one-half thereof in order to accommodate a cooperating flange member 60 on the auxiliary handle 52. Member 58 is formed with a central opening 61 and on its interior surface the same is provided with diametrically spaced lugs 62. The handle 52 has a length substantially the same as the pistol grip and by means of the flange portion 60 it is possible to secure this auxiliary handle to the adapter in one of several adjusted positions. A central opening 63 extends through portion 60 and said opening is aligned with opening 61, the same receiving a screw 64 whereby the parts are releasably held in associated relationship. The interior surface of portion 60 is formed with two groups of recesses 65, the groups being diametrically opposed and adapted to receive the lugs 62 which thereby locks the handle member in any desired position as permitted by the recess.

With the auxiliary handle 52 in an intermediate position, as shown in full lines in Figure 5, the same provides an extension of the pistol grip and enables the operator to grasp the device of the invention with both hands. This is desirable for certain classes of work where the articles picked up by the device are relatively heavy. If at any time the operator is required to handle light articles, in which case the auxiliary handle member would be superfluous, the same can be easily removed from the pistol grip by removal of screw 64. This removal of the auxiliary handle however does not change the permanent securement of the handle adapter to the pistol grip.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In a safety tool, a member in the form of a pistol grip providing a handle therefor, a longitudinal bore extending the length of the member, a venturi passage extending transversely of the member in the upper portion thereof and intersecting the longitudinal bore, valve means for controlling the flow of a fluid medium through the longitudinal bore, a suction passage in the handle member having communication with the venturi passage, and vacuum producing means in said venturi passage including a jet and a venturi member, the discharge end of the jet having location within the venturi member on the side of the suction passage opposite the longitudinal bore.

2. In a safety tool, a member in the form of

a pistol grip providing a handle therefor, a tubular supporting arm extending forwardly of the member for supporting a suction gripping cup, a longitudinal bore running the length of the member, a venturi passage located in the upper portion of the member and intersecting the longitudinal bore, a valve chamber in the member also intersecting the longitudinal bore in advance of the intersection therewith of the venturi passage, valve means mounted within said chamber for controlling the flow of a fluid medium through the longitudinal bore, a suction passage connecting the venturi passage with said tubular supporting arm, and vacuum producing means in the venturi passage located on the side of the suction passage opposite the longitudinal bore.

3. In a safety tool, a member in the form of a pistol grip providing a handle therefor, a longitudinal bore extending the length of the member, a venturi passage extending transversely of the member in the upper portion thereof and intersecting the longitudinal bore, valve means for controlling the flow of a fluid medium through the longitudinal bore, a suction passage in the handle member having communication with the venturi passage, a venturi member mounted in one end of the venturi passage and projecting forwardly of the pistol grip, and a jet holder also mounted within the venturi passage in associated relation with the venturi member, said jet holder being insertable and removable from the end of the passage opposite the venturi member.

4. In a safety tool, a member in the form of a pistol grip providing a handle therefor, a longitudinal bore extending the length of the member, a venturi passage extending transversely of the member in the upper portion thereof and intersecting the longitudinal bore, valve means for controlling the flow of a fluid medium through the longitudinal bore, a suction passage in the handle member having communication with the venturi passage, a venturi member mounted in the venturi passage and disposed to one side of the intersection of the suction passage therewith, and a jet holder mounted in the venturi passage and located to the other side of said intersection, said jet holder being insertable and removable from the end of said passage opposite the venturi member.

5. In a device of the character described, a member in the form of a pistol grip providing a handle therefor, a venturi passage extending transversely of the member in the upper portion thereof, a suction passage extending vertically from the top surface of the pistol grip and intersecting the venturi passage, a longitudinal bore also extending vertically from the top surface of the pistol grip and intersecting the venturi passage, an adapter having an undersurface shaped for association with the top surface of the pistol grip, and screws for securing the adapter to the pistol grip, said screws having threaded connection with the pistol grip in the openings leading to the suction passage and longitudinal bore respectively.

EDGAR R. MILLER.
